UNITED STATES PATENT OFFICE.

ELIAS M. AVERILL, OF SPARTA, MICHIGAN.

FOLDING CRATE.

Application filed October 17, 1921. Serial No. 508,217.

To all whom it may concern:

Be it known that I, ELIAS M. AVERILL, a citizen of the United States, residing at Sparta, in the county of Kent and State of Michigan, have invented a new and useful 5 Folding Crate, of which the following is a specification.

This invention relates to crates or the like, and more particularly to a novel form of 10 folding crate which may be folded into a comparatively small and compact article for return shipment.

The primary object of the invention is to provide a crate of this character wherein the 15 corner connecting members will move, to permit the cover to be secured, it being contemplated to move the end members of the crate to spring the cover in place.

Another object of the invention is to provide 20 novel means for securing the corner members to the staves or slats of the crate.

With the foregoing and other objects in view which will appear as the description proceeds, the invention resides in the combination and arrangement of parts and in the details of construction hereinafter described and claimed, it being understood 25 that changes in the precise embodiment of the invention herein disclosed, may be made 30 within the scope of what is claimed, without departing from the spirit of the invention.

Referring to the drawing:—

Figure 1 is a plan view of a crate constructed 35 in accordance with the present invention, showing one end of the crate in dotted lines, as sprung outwardly to permit the cover to be sprung into place.

Figure 2 is an end elevational view of the 40 plate in its folded position.

Figure 3 is a fragmental detail view, the same being shown in section and taken on line 3—3 of Figure 1.

Figure 4 is a sectional view taken on line 45 4—4 of Figure 1.

Figure 5 is a sectional detail view disclosing the connection between the ends of side and end stays.

Referring to the drawing in detail, the 50 crate embodies side and end members formed of a plurality of longitudinal spaced staves 5, which have slots formed in the ends there-

of to accommodate the metallic corner members 6, which are in the forms of strips of flexible metal bent intermediate their side 55 edges as clearly shown by Figure 5 of the drawing. Suitable securing means such as bolts 7 may be passed through the staves and through the corner members 6, as shown by Figure 5 of the drawing.

The cover which is indicated at 8, is also formed of a plurality of spaced staves connected by means of the bars 9, the ends of the staves being disposed under the bars 10 which are secured to the uppermost 65 staves of the ends of the crate. The bars 9 are of lengths to extend over the upper edges of the uppermost staves of the crate, as clearly shown by Figure 1 of the drawing, so that the cover 8 will be held in position 70 thereon. It follows that when a cover is to be positioned, one end of the crate is sprung or bowed, as shown by Figure 1 of the drawing. One end of the cover is now positioned under one of the bars 10, and with 75 the opposite end of the crate in a bowed position, the cover may be easily forced downwardly and into place.

It will thus be seen that when the end member of the crate has been released, the 80 flexibility of the corner member 6 returns the staves of the end members to their lower positions.

If it is desired to fold the crate, the cover and bottom thereof, which it might be stated 85 is identical with the cover structure, are removed, and the body portion of the crate folded to a position as indicated by Figure 2 of the drawing.

Having thus described the invention, what 90 is claimed as new is:—

A crate embodying side and end members, strips of flexible metal connecting the side and end members, said flexible metal adapted to permit the end members to be bowed 95 outwardly to position a cover thereon.

In testimony that I claim the foregoing as my own, I have hereto affixed my signature in the presence of two witnesses.

ELIAS M. AVERILL.
